UNITED STATES PATENT OFFICE.

CHARLES KINZLER AND WM. ROSEBUCK, OF NEW YORK, N. Y.

IMPROVED SUGAR-CUTTER.

Specification forming part of Letters Patent No. 27,135, dated February 14, 1860.

To all whom it may concern:

Be it known that we, CHARLES KINZLER and WILHELM ROSEBUCK, both of the city of New York, in the county and State of New York, have invented a new and improved machine for cutting loaf-sugar in square and regular pieces; and we hereby declare that the following is a full and exact description of the same, reference being had to the accompanying drawings and to the letters of reference marked thereon.

Figure I represents partly a longitudinal section and partly an outside view of the machine, and Fig. II represents a cross-section; Fig. III, a top view of the machine.

The nature of our invention consists in an arrangement for cutting loaf-sugar into systematic, regular, and equal pieces. For this purpose the loaf-sugar is first, by means of circular or other saws, cut into slices or slabs of about one inch or three-quarters of an inch in thickness. The slices or slabs are then brought into the machine to be cut into small morsels. On a table, A, plates B B are fixed capable of moving. The central parts of these plates are provided with blades or knives o crossing each other at right angles and forming squares of a size equal to the required size of the morsels, and forming a grating in the central part of those plates B B, and so arranged that the cutting-edges in both plates correspond with each other. When said plates are moved toward each other, after the slices or slabs of sugar have been introduced, the slices are subjected thereby to a pressure and are cut or cracked on both sides into the re-

quired morsels. Behind the plates B B frames C C are firmly fastened to the table or frame A and provided with pins or projections m, having flat plates n on their ends, which enter the hooks between the knives o when the plates B are receding, so as to push off any morsels which may remain fast in the grating or between the knives. The plates B B are moved toward and from each other by means of rods p p, attached to levers q, operated from the shaft V, or any other mechanical arrangement.

Instead of moving the two plates B B, as above described, one of the frames C may be attached to the opposite plate B, and those two moved together, while the other frame C and plate B remain stationary, by which arrangement the same results will be obtained.

What we claim as our invention and desire to secure by Letters Patent, is—

The arrangement to two plates provided with knives forming square openings, and capable of moving toward and from each other, for the purpose of cutting or cracking the slabs of sugar into regular morsels, in combination with fixed frames provided with points which enter the openings in said plates when the latter are receding for the purpose of pushing the morsels or pieces which may adhere to the knives out of the holes, and operating together in the manner and for the purpose substantially described and specified.

CHARLES KINZLER.
WILHELM ROSEBUCK.
